UNITED STATES PATENT OFFICE

133,726

DESIGN FOR A COMBINED WIRED CHENILLE AND FELT STRIPPING

Bernard Workman, New York, N. Y.

Application June 4, 1942, Serial No. 107,117

Term of patent 7 years

To all whom it may concern:

Be it known that I, Bernard Workman, a citizen of the United States of America, residing in New York city, county of New York and State of New York, have invented a new, original, and ornamental Design for a Combined Wired Chenille and Felt Stripping, of which the following is a specification, reference being had to the accompanying drawing, forming part thereof.

Fig. 1 is a front view of a combined wired chenille and felt stripping showing my new design.

Fig. 2 is an edge view thereof.

Fig. 3 is a rear view.

I claim:

The ornamental design for a combined wired chenille and felt stripping, substantially as shown.

BERNARD WORKMAN.
